(57) **CLAIM**

The ornamental design for pot handles, as is shown and described.

DESCRIPTION

FIG. 1 is a perspective view of pot handles, showing our new design, in a position of use with exemplary environmental subject matter of a pot;

FIG. 2 is a top plan view thereof;

FIG. 3 is a left side elevational view thereof;

FIG. 4 is a right side elevational view thereof;

FIG. 5 is a front side elevational view thereof;

FIG. 6 is a rear side elevational view thereof; and,

FIG. 7 is a bottom plan view thereof.

The broken lines are shown for the purpose of illustrating environmental subject matter of an exemplary pot and form no part of the claim.

1 Claim, 7 Drawing Sheets
